UNITED STATES PATENT OFFICE.

ALOYSIUS L. MAHONY, OF BOSTON, AND PETER J. LINSTROM, OF MEDFORD,
MASSACHUSETTS.

SIGNALING DEVICE.

Application filed August 15, 1923. Serial No. 657,496.

To all whom it may concern:

Be it known that we, ALOYSIUS L. MAHONY and PETER J. LINSTROM, citizens of the United States, residing at Boston and

5 Medford, in the counties of Suffolk and Middlesex, respectively, and State of Massachusetts, have invented new and useful Improvements in Signaling Devices, of which the following is a specification.

10 This invention relates chiefly to signaling devices for motor vehicles, adapted to notify street traffic of an intended turn to right or left, as well as of a continuation of a forward movement, without turning.

15 One object of the invention is to provide a signaling device which may be successfully used in an elevated and conspicuous position on the body of a closed motor car, and higher than the roof, so that the 20 acting portion of the device may be seen from the front, rear, and both sides of the vehicle.

Another object is to provide practical, durable, and relatively inexpensive means 25 for operating an elevated signal on a motor car, from a point in convenient reach of the driver.

Other objects will hereinafter appear.

Of the accompanying drawings forming 30 a part of this specification,—

Figure 1 shows partly in section and partly in elevation, the portion of a signaling device embodying the invention, which includes the direction-indicator and its 35 support.

Figure 2 shows partly in section and partly in elevation, the portion of the signaling device which includes the controlling valve.

40 Figures 3 and 4 are top plan views of the portion shown by Figure 1.

Figure 5 is a perspective view, showing a portion of a motor car having a signaling device embodying the invention, the air 45 conduits and the vacuum conduit herein-after described being shown diagrammatically.

Figures 6, 7 and 8 are side views of the controlling valve showing the same on different adjustments.

Figure 9 is a section on line 9—9 of Figure 1.

Figures 10 and 11 are perspective views, showing the members of the controlling 55 valve separated from each other.

Figure 12 is a view partly in section and partly in elevation, showing a modification.

The same reference characters indicate the same parts in all of the figures.

12 represents a casing adapted to contain an electric lamp 13, and fixed to a tubular shaft 14, adapted to receive the socket of the lamp, as shown by Figure 1. The casing is elongated in a direction substantially at right angles with the axis of the shaft, 60 and has an enlarged end which may be provided with a lens 15, and a reduced, preferably pointed, opposite end, the form of the casing being such that it constitutes a pointer. The opposite sides of the casing have preferably triangular openings 16, 65 adapted to transmit light from the lamp.

The shaft 14 is journaled in bearings 17 and 18, formed in the top and bottom of a piston chamber 19. Said chamber is 70 substantially semicircular, as shown by Figure 9, and is provided in this instance with means whereby it may be attached to the upper portion of the closed body 20 of a motor car, the back of the chamber 75 being preferably flat and provided with ears 21, attachable as by screws 22 to a vertical side portion of the body. The arrangement is such that when the piston chamber is in the predetermined position on the body 20, the axis of the shaft 14 is substantially vertical, and the axis of the lamp casing substantially horizontal. The location of the piston chamber shown by Figure 5 is such that the lamp casing is close to 80 and higher than the front end of the body, and is at one corner of the latter, so that the casing may be clearly seen from the front, the rear, and both sides of the vehicle.

The lamp casing shaft 14 is provided 85 within the chamber 19 with a wing piston 23, movable, by fluid pressure in the chamber, to either of the positions indicated by full and dotted lines in Figure 9, the shaft and the lamp casing being moved by the 90 piston to corresponding positions, as indicated by full and dotted lines by Figures 3 and 4. When the piston is in the full line position, the lamp casing is positioned as shown by Figure 3, its major axis extending 95 lengthwise of the body 20, and its end facing forward. When the piston is in the right hand dotted line position, the lamp casing is positioned as shown by full lines by Figure 4, its major axis extending 100 lengthwise of the body 20, and its end facing forward. When the piston is in the left hand dotted line position, the lamp casing is positioned as shown by full lines by Figure 5, its major axis extending 105 lengthwise of the body 20, and its end facing forward. When the piston is in the right hand dotted line position, the lamp casing is positioned as shown by full lines by Figure 6, its major axis extending 110 lengthwise of the body 20, and its end facing forward.

crosswise of the body and the casing pointing toward the right. When the piston is in the left hand dotted line position, the lamp casing is positioned as shown by dotted lines in Figure 4, the casing pointing toward the left. The direction of the vehicle, when it is moving forward, is indicated by the arrow *x*.

The piston is caused to assume either of 10 the described positions by air pressure controlled by the driver through the means next described.

Mounted on the vehicle dash, or other suitable support, is a valve comprising a fixed 15 member 25, fixed as by screws 26, to a holder 27, attached to the dash; and a movable member 28, adapted to turn on the fixed member, and maintained in close sliding contact therewith, by a spring 29, supported by 20 a stem 30, which is fixed to the movable member and extends through a central orifice 31, in the fixed member, the spring bearing on a fixed abutment 32, and on a nut 33, carried by the stem, as shown by Figure 2.

25 A suction conduit 34 extends from the intake manifold 35 of the engine to and through the fixed valve member 25. Said suction conduit is in constant open connection with the valve and with the manifold, 30 so that suction is constantly exerted in all parts of the conduit. Air conduits 36, 37 and 38 passing through the fixed valve member, extend therefrom through the wall and to the cavity of the piston chamber 19.

35 The exposed portions of the several conduits are preferably lengths of copper or brass tubing, the end portions being holes formed in the valve and piston casings. The movable valve member 28 has a channel 40 adapted to selectively connect the air conduits 36, 37 and 38 with the suction conduit 34, and is provided with air ports 30 and 40, which selectively open different air conduits to the atmosphere, all as herein-after explained.

The said channel is preferably formed as shown by Figure 11, and includes segmental portions 41 and 42, an annular portion 43, and portions 44 connecting the segmental 50 portions with the annular portion.

The movable valve member 28 is provided with a handle 45, having a spring-pressed 55 detent 46, adapted to engage either of a series of indentations 47 in the holder 27, and retain the handle and the movable member in different positions.

The operation is illustrated by Figures 6, 7, 8 and 9.

When the handle 45 is moved to the position shown by Figure 6, the movable valve member 28 connects the air conduit 37 with the suction conduit 34, through the described channel portions, the conduits 36 and 38 being closed. Air is now simultaneously 60 drawn from the piston chamber at one side

of the piston through the exhaust conduit 34, and into the chamber at the opposite side of the piston through the air conduit 37, until the piston reaches the full line position in Figure 8, and closes said conduit 34, whereupon the piston stops with the lamp casing in its neutral position (Figure 3).

When the handle is moved to the left as shown by Figure 7, the movable valve member connects the air conduit 38 with the suction conduit 34, the conduit 36 being closed and the conduit 37 opened to the atmosphere through the air port 40. Air is now simultaneously drawn from the piston chamber at one side of the piston through the exhaust conduit and into the chamber at the opposite side of the piston through the air conduit 38, until the piston reaches the right hand dotted line position (Figure 9), the lamp casing being now in the full line position (Figure 4).

When the handle is moved to the right as shown by Figure 8, the movable member connects the air conduit 36 with the suction conduit 34, the conduit 38 being closed and the conduit 37 opened to the atmosphere through the air port 39. Air is now simultaneously drawn from the piston chamber at one side of the piston through the exhaust conduit, and into the chamber at the opposite side of the piston through the air conduit 36, until the piston reaches the left hand dotted line position (Figure 9), the lamp casing being now in the dotted line position (Figure 4).

By pneumatically operating a direction-indicating lamp casing, the complication and liability to derangement of means including flexible cables heretofore employed for a similar purpose are avoided, and the lamp casing is located in a position which is higher and more conspicuous than heretofore.

Figure 12 shows a modified form of means for turning the lamp casing in which the tubular shaft 12^a of the lamp casing is journaled in bearings 17^a and 18^a in a piston chamber formed as a cylinder 50. A piston 51 is adapted to reciprocate in the cylinder 115 and has a rack 52 meshing with a gear 53 on the shaft. Air conduits 36^a and 38^a corresponding to the conduits 36 and 38, enter opposite ends of the piston. An air conduit 37^a corresponding to the conduit 37 has branches 37^b entering the cylinder between the ends thereof, and arranged to be closed by the piston when the lamp casing reaches a neutral position. The general operation is as already described.

The lighting circuit which includes the lamp 13, and is shown diagrammatically by Figure 8, includes a switch, operated automatically to extinguish the lamp when the casing is in its neutral or longitudinal position, the lamp being lighted only when the 120 125 130

casing points crosswise. The switch as shown by dotted lines in Figures 6, 7 and 8, includes a fixed member 54 having two spaced apart contacts 55 and a movable member 56 having a single contact 57, and engaged with the movable valve member. When the movable valve member is in the position shown by Figure 7, or that shown by Figure 8, the contact 57 touches one of the contacts 55. When the movable member is in the position shown by Figure 6, the contact 57 is separated from each of the contacts 55.

The piston chamber, the piston, the air conduits, the controlling valve, the suction conduit, and the intake manifold, constitute an embodiment of a motor, whereby the lamp casing may be moved to, and left in the different positions described, the motor furnishing the motive power, so that the muscular force of the operator is exerted only to move the movable valve member.

Although the motor here shown is pneumatic, the invention is not necessarily limited to a motor of this type as implied in certain of the following claims.

The employment of a motor operated by force other than the muscular force of a driver, is believed to be new in a signaling device of the type described, and enables the lamp casing to be located and successfully operated in a position elevated above the roof of a closed vehicle body. The intake manifold is selected as the most convenient form of air-exhausting means. It is obvious, however, that other means may be employed for exhausting air through the suction conduit.

We claim:

40. 1. A signaling device comprising a dirigible direction-indicating lamp casing, a shaft supporting the same and arranged substantially at right angles with the major axis of the lamp casing, a pneumatic motor including a piston chamber provided with bearings for said shaft and with means for attachment to a vehicle body, in position to maintain said shaft substantially vertical, a manually operable controlling valve, a plurality of air conduits connecting different portions of the piston chamber with different portions of the controlling valve, air-exhausting means carried by the vehicle, and a suction conduit connecting said valve with said air-exhausting means and in constant open communication with the valve and with the air-exhausting means, said valve being provided with means for selectively connecting either of the air conduits with the suction conduit and with the atmosphere.
  45. 2. A signaling device comprising a dirigible direction-indicating lamp casing, a shaft supporting the same and arranged substantially at right angles with the major axis of the lamp casing, a pneumatic motor including a piston chamber provided with bearings for said shaft and with means for attachment to a vehicle body, in position to maintain said shaft substantially vertical, a manually operable controlling valve, a plurality of air conduits connecting different portions of the piston chamber with different portions of the controlling valve, air-exhausting means carried by the vehicle, and a suction conduit connecting said valve with said air-exhausting means and in constant open communication with the valve and with the air-exhausting means, said controlling valve comprising a fixed member with which said air conduits and suction conduit are engaged, a movable member and spring means maintaining the movable member in sliding contact with the fixed member, said
- of the lamp casing, a pneumatic motor including a piston chamber provided with bearings for said shaft and with means for attachment to a vehicle body, in position to maintain said shaft substantially vertical, a manually operable controlling valve, a plurality of air conduits connecting different portions of the piston chamber with different portions of the controlling valve, air-exhausting means carried by the vehicle, and a suction conduit connecting said valve with said air-exhausting means, and in constant open communication with the valve and with the air-exhausting means, said valve being provided with means for selectively connecting either of the air conduits with the suction conduit and with the atmosphere.
3. A signaling device comprising a dirigible direction-indicating lamp casing, a shaft supporting the same, and arranged substantially at right angles with the major axis of the lamp casing, a motor including a wing piston on said shaft, a substantially semicircular piston chamber provided with bearings for said shaft, formed internally to cooperate with said piston, and provided with means for attachment to a vehicle body in position to maintain the shaft substantially vertical, a manually operable controlling valve, a plurality of air conduits connecting different portions of the piston chamber with different portions of the controlling valve, air-exhausting means carried by the vehicle, and a suction conduit connecting said valve with said air-exhausting means, and in constant open communication with the valve and with the air-exhausting means, said valve being adapted to selectively connect either of the air-conduits with the suction conduit.
4. A signaling device comprising a dirigible direction-indicating lamp casing, a shaft supporting the same and arranged substantially at right angles with the major axis of the lamp casing, a pneumatic motor including a piston chamber provided with bearings for said shaft and with means for attachment to a vehicle body, in position to maintain said shaft substantially vertical, a manually operable controlling valve, a plurality of air conduits connecting different portions of the piston chamber with different portions of the controlling valve, air-exhausting means carried by the vehicle, and a suction conduit connecting said valve with said air-exhausting means and in constant open communication with the valve and with the air-exhausting means, said valve comprising a fixed member with which said air conduits and suction conduit are engaged, a movable member and spring means maintaining the movable member in sliding contact with the fixed member, said

movable member being provided with an operating handle, whereby it may be turned, and with connected channel portions adapted to selectively connect either of the air conduits with the suction conduit.

5. A signaling device comprising a dirigible direction-indicating lamp casing, a shaft supporting the same, and arranged substantially at right angles with the major 10 axis of the lamp casing, a motor including a wing piston on said shaft, a substantially semicircular piston chamber provided with bearings for said shaft, formed internally to cooperate with said piston, and provided 15 with means for attachment to a vehicle body in position to maintain the shaft substantially vertical, a manually operable controlling valve, a plurality of air conduits con-

necting different portions of the piston chamber with different portions of the controlling valve, air-exhausting means carried by the vehicle, and a suction conduit connecting said valve with said air-exhausting means and in constant open communication with the valve and with the air-exhausting means, said valve being adapted to selectively connect either of the air conduits with the suction conduit, said movable member being also provided with air ports adapted to selectively open different air conduits to the atmosphere.
